UNITED STATES PATENT OFFICE.

FRANK L. JERAULD, OF CRANSTON, RHODE ISLAND, ASSIGNOR TO WINSOR & JERAULD MFG. CO., OF PROVIDENCE, RHODE ISLAND, A CORPORATION OF MAINE.

TENTER CLIP.

Application filed January 19, 1928. Serial No. 247,786.

This invention relates to an improved construction of tenter clip and has for its object to provide a clip of this character which is adapted for engaging open mesh fabric, more particularly wire fabric, the clip having means for entering the meshes of the fabric to hold its edge against tension.

A further object of the invention is the provision of a clip of this character having a guide portion for the support of the margin of the fabric and having a blade or member with an edge portion arranged to ride on the selvage of the fabric as the selvage is being drawn outwardly toward the mouth of the clip, the blade being also provided with a hook or engaging end portion shaped to enter the meshes of the fabric to retain the fabric in the clip, when under tension.

A still further object of the invention is the provision of a clip having a plurality of independently movable members arranged to separably enter the meshes of the fabric to retain the same, whereby if one or more of the engaging members should for any cause fail to enter the meshes of the fabric such action would not prevent the others of the engaging members of the set from functioning.

With these and other objects in view, the invention consists of certain novel features of construction, as will be more fully described, and particularly pointed out in the appended claims.

In the accompanying drawings:

Figure 1 is a top view illustrating my improved tentering clip and showing in dotted lines a section of open mesh fabric such as wire fabric as engaged by the clip.

Figure 2 is a perspective view of one of the mesh fabric engaging members or blades.

Figure 3 shows the body of the clip with a slotted guide for the fabric and a plurality of spaced openings in which the mesh engaging members are to be mounted.

Figure 4 is a side elevation illustrating one of the mesh engaging members as having a portion riding upon the selvage of the fabric and being held out of engaging position thereby.

Figure 5 shows the selvage as having been withdrawn from beneath the guiding portion of the engaging member and permitting the member to drop and cause its hook portion

to engage the mesh and engage the selvage of the fabric.

Figure 6 is a section on line 6—6 of Figure 5 showing the plurality of engaging members as hooked over the margin of the fabric in extending thru the meshes thereof to retain the fabric against a stretching tension.

It is found in practice that owing to the stiff and uneven or wavy condition of the edges of wire mesh fabric that the ordinary tenter clip in a tentering machine cannot be relied upon to engage the margin of this fabric for stretching the same and therefore in order to provide a clip which will act upon fabric of this character, I have provided one having a body portion which is slotted to receive the margin of the fabric and so assist in straightening out some of the bends in its wires as the same is drawn into the clip and I have provided in the clip one or more fingers or members preferably a plurality each shaped at its end portion to independently enter the open meshes of the fabric and so retain the fabric while receiving the tensioning action, also I preferably so form these engaging members that they will ride on the margin of the fabric and so be retained out of engaging position until this margin is withdrawn to a predetermined position at which time these members are permitted to freely drop into the meshes in the fabric and engage the margin thereof to securely retain the fabric against the spreading tension. By employing a plurality of these members I insure the engaging of one or more of them into the meshes of the fabric and that the refusal of one or more to drop by coming in contact with portions of the wire or other reasons will not prevent the others from functioning; and the following is a detailed description of the present embodiment of my invention and showing one construction of clip by which these advantageous results may be accomplished.

With reference to the drawings 10 designates the body of the clip which is carried on and secured to the usual chain link portion 11. This body portion is provided with a longitudinal slot or guide 12 open at its front and sides to receive and guide the margin 13 of the wire fabric. The edges 14 of this slot are preferably rounded as best illus-

trated in Figure 6 to smoothly guide the marginal edge of the fabric, which is more or less wavy, thereinto.

This body member is herein shown as being of a substantial width and provided with a plurality of spaced slots 15 thru the upper wall 16 thereof and corresponding recesses 17 in the lower plate 18 thereof. This lower plate is provided with holes 19 therethrough to receive the ends of the hook, presently described and also to permit flakes of the metal to fall therethrough and so prevent clogging. This body portion is also provided with spaced pivot ears 20 through which a pivot pin 21 extends.

On this pivot pin, I have herein shown as being mounted a plurality of fabric engaging blades 22 to swing vertically through the slots 15 and across the longitudinal or fabric receiving slot 12, the lower edge 23 of each blade is formed straight so as to rest or ride upon the margin or selvage wire 13 of the wire fabric and the outer end of this blade is notched as at 24 to provide a hook or engaging portion so shaped that when the margin of the fabric is drawn outwardly from under the riding portion 23 of the blade, the notch 24 in this plate or other shape will permit the blade to drop into the position best illustrated in Figure 5 and so cause the portion 25 to enter the mesh and engage the marginal wire 13 of the fabric and hold it against being withdrawn from the clip.

Each of these blades is provided with a rearwardly extending portion 26 to be engaged by the usual part not shown of a tentering machine to lift the blade at one end of the machine to permit the entrance of the fabric into the clip and at the opposite end of the tentering machine to lift and disengage these hooks or retainer members from the meshes of the fabric after it has been operated upon.

It will be observed that by my improved clip wherein I employ a plurality of engaging members which operate entirely independently of each other that the failure of one or more to enter the meshes of the fabric would not prevent the other from functioning which might not be the case if all the members were connected to operate as a single unit.

My improved tensioning clip is very simple and practical in construction, is strong and durable and effective in its operation and by its use wire fabric may be operated upon to receive the stretching action of a tentering machine.

The foregoing description is directed solely towards the construction illustrated, but I desire it to be understood that I reserve the privilege of resorting to all the mechanical changes to which the device is susceptible, the invention being defined and

limited only by the terms of the appended claims.

I claim:

1. A tenter clip for open mesh fabric, comprising a body member having spaced upper and lower guide members for guiding the fabric into the clip, and a cooperating swinging member having means for entering the meshes of the fabric to hold its edge against tension. 75

2. A tenter clip for open mesh fabric, comprising a body member having spaced plates arranged to guide the margin of the fabric into the clip, a cooperating fabric engaging member pivoted to swing across 80 the margin of the fabric in the clip and carrying means for entering the meshes of the fabric to hold its edge against tension.

3. A tenter clip for open mesh fabric, comprising a body member having a pair of spaced guide members arranged to guide the fabric into the clip, a cooperating retaining member pivoted at its rear end to swing across the margin of the fabric in the clip, said member carrying means for entering the 90 meshes of the fabric, and means in said member arranged to ride on the fabric and control the fabric engaging action of said member. 85

4. A tenter clip for open mesh fabric, comprising a guide for the fabric, a pivoted member having a guiding part arranged to ride on the selvage of the fabric, and an engaging part arranged to enter the meshes of the fabric when the selvage is withdrawn 100 from the guiding part of the member to retain the fabric against tension. 95

5. A tenter clip for open mesh fabric comprising a body portion slotted to receive the edge of the fabric, and a pivoted member controlled in its mesh engaging action by engagement with the fabric in the slot and having a portion arranged to extend across said slot into the mesh of the fabric to retain the same against tension. 105 110

6. A tenter clip for open mesh fabric comprising a guide for supporting the margin of the fabric, a pivoted blade arranged to swing at right angles to the margin of the fabric in the clip, said blade having a guide edge positioned to ride on the selvage of the fabric, said blade also having a hook shaped portion adjacent its end to enter the meshes of the fabric as the selvage is withdrawn from the blade support to retain the 115 120 fabric under tension.

7. A tenter clip for open mesh fabric comprising a body slotted to receive the margin of the fabric, a pivoted blade arranged to swing across the slot and ride on the selvage 125 of the fabric in the clip and said blade having a hook shaped end portion to enter the meshes of the fabric as the selvage is withdrawn from the blade support to retain the fabric under tension. 130

8. A tenter clip for open mesh fabric comprising a body member having spaced plates arranged to provide a guide for the fabric in entering the clip, and a plurality of independently movable members arranged to enter the meshes of the fabric to retain the same against tension.

9. A tenter clip for open mesh fabric comprising a body member having upper and lower spaced members cooperating to provide a guide for conducting the fabric into the clip and a plurality of movable members arranged to extend across said guide slot and independently enter the meshes of the fabric to retain the same against tension.

10. A tenter clip for open mesh fabric comprising a guide for supporting the margin of the fabric, a plurality of cooperating independently operating retaining members, each having a portion arranged to ride on the selvage of the fabric and having a portion shaped to enter the meshes of the fabric as the selvage is withdrawn from the riding portion, said entering portion serving to retain the fabric against tension.

11. A tenter clip for open mesh fabric comprising a guide for supporting the margin of the fabric, a plurality of independently operable pivoted retaining members, each having a portion arranged to ride on the selvage of the fabric and an engaging portion to extend through the meshes of the fabric when the selvage is withdrawn from the riding portion, said engaging portion serving to retain the fabric against tension.

12. A tenter clip for open mesh fabric

comprising a guide for supporting the margin of the fabric, a plurality of independently operable pivoted blades, each having an edge portion arranged to ride on the selvage of the fabric, and a hook shaped portion at the end of the blade to enter the mesh of the fabric when the selvage is withdrawn from the riding portion of the blade to retain the fabric against tension.

13. A tenter clip for open mesh fabric comprising a slotted guide to receive the margin of the fabric, a plurality of cooperating independently operable members, means acting on each member to hold it from operating position until the margin of the fabric has been withdrawn to a predetermined position in said slot and an engaging portion on said members to enter the meshes of the fabric when so positioned to retain the fabric against tension.

14. A tenter clip for open mesh fabric comprising a slotted guide to receive the margin of the fabric, a plurality of pivot blades, each having an edge portion to ride on the selvage of the fabric and mounted to swing across the slot as the selvage is drawn outwardly therefrom, each of said blades having an engaging end portion shaped to enter the meshes of the fabric when the margin of the fabric is withdrawn to a predetermined position to retain the fabric under tension.

In testimony whereof I affix my signature.

FRANK L. JERAULD.
